US0D1101154S

(12) **United States Design Patent** (10) **Patent No.:** **US D1,101,154 S**
(45) **Date of Patent:** **** Nov. 4, 2025**

(54) **CPAP ARM BAND**

(71) Applicant: **Vinco CPAP, LLC**, Sioux Falls, SD (US)

(72) Inventor: **Kevin M. Faber**, Marshfield, WI (US)

(73) Assignee: **VINCO CPAP, LLC**, Marshfield, WI (US)

(**) Term: **15 Years**

(21) Appl. No.: **29/822,793**

(22) Filed: **Jan. 12, 2022**

(51) LOC (15) Cl. **24-02**

(52) U.S. Cl.

USPC **D24/164**; D24/190

(58) **Field of Classification Search**

USPC D24/110-110.6, 127, 129, 135, 164, 169, D24/188-192; D29/110, 108; D2/891, D2/979, 610; D6/682, 682.4, 682.5, 319, D6/328; D3/215, 327

(57) **CLAIM**

The ornamental design for a CPAP arm band, as shown and described.

DESCRIPTION

FIG. 1 is a perspective view of a first embodiment of a CPAP arm band showing a new design;

FIG. 2 is another perspective view thereof;

FIG. 3 is a top view thereof;

FIG. 4 is a bottom view thereof;

FIG. 5 is a front view thereof;

FIG. 6 is a back view thereof;

FIG. 7 is a left side view thereof;

FIG. 8 is a right side view thereof;

FIG. 9 is a perspective view of a second embodiment of a CPAP arm band showing another new design;

FIG. 10 is another perspective view thereof;

FIG. 11 is a top view thereof;

FIG. 12 is a bottom view thereof;

FIG. 13 is a front view thereof;

FIG. 14 is a back view thereof;

FIG. 15 is a left side view thereof; and,

FIG. 16 is a right side view thereof.

The broken lines within the CPAP arm band show portions of the CPAP arm band that form no part of the claimed design. The broken lines in FIG. 1 showing a person and setting depict environment that forms no part of the claimed design.

The CPAP arm band in FIGS. 9-16 is shown with symbolic breaks in its length and width. The appearance of any portion of the article between the break lines forms no part of the claimed design.

1 Claim, 12 Drawing Sheets
